UNITED STATES PATENT OFFICE.

WILLIAM HERBERT NIELD, OF STOCKPORT, ENGLAND.

FURNACE GRATE.

Application filed March 25, 1920. Serial No. 368,927.

To all whom it may concern:

Be it known that I, WILLIAM HERBERT NIELD, subject of the King of Great Britain, residing at Stockport, in the county of Cheshire and Kingdom of England, have invented certain new and useful Improvements in and Relating to Furnace Grates, of which the following is a specification.

The present invention relates to improvements in the grates of boilers and the like furnaces.

According to this invention a grate formed of a plurality of bars or links is provided with means to cause the links to be raised in groups in sequence along the grate whereby the depth of the fuel bed tends to be maintained constant throughout.

By this means the appearance of holes in the fire, which not only affect efficient combustion of the fuel on the grate due to irregularity of draft, but also cause a more rapid destruction of the bars or links forming the grate is avoided.

The invention is more particularly described with reference to the accompanying drawings in which:

Figure 1 is a sectional elevation through a fire chamber of a boiler showing the links connected together.

Fig. 2 is a sectional elevation on the line 2—2 of Fig. 1.

Figs. 3—4 are diagrammatic views showing the motion of the separate links to form a wave.

Fig. 5 shows in detail the reversing means.

A furnace of any desired form whatever is provided with a grate comprising a plurality of bars or links 1 linked end to end in a manner similar to a chain grate; the grate so formed being supported at its two ends 2, 3. The grate is longer than the distance between the fastenings 2, 3, by preferably at least the length of an individual link 1.

A knobbed roller 5 freely mounted on a carriage 6 moving on guides 7 mounted on the walls 8 of the furnace, is so arranged that when the knobbed roller moves longitudinally of the grate, it takes up the slack of the grate and forms a hump or projection which moves in conjunction with the movement of the knobbed roller 5. The roller rotates as it progresses along and thereby raises the links.

The carriage 5 comprises a spindle 35 on which are mounted flanged rollers 37 contacting with the guides 7, and a central portion 38 adapted to be secured to a cable 9, said cable forming the means for moving the carriage 6 and rollers 5 longitudinally of the grate. Freely mounted at each end of the spindle 35 is a depending arm 36 to which is secured a perforated pipe 11; a flexible conduit 10 being connected to said pipe to provide means by which cooling water or steam may be delivered hereto for spraying onto the under part of the said links.

The carriage 6 may move forward or backward with its rollers 37 on the guides 7 with the roller 5 in raising engagement with the grate, or it may likewise move forward or backward, with its rollers, upon the additional guides 39 with the roller 5 out of such raising engagement with the grate. In either case, it is moved by the cable 9. During this latter movement also the pipe 11 carried by the pivotal arms 36 will ride on the supplementary guides 39 usually in front of the carriage 6.

It will be seen that as the raising roller 5 meets the links *a, b*, these are lifted to initially present a channel or inverted V cross section (Fig. 3); and as the motion progresses, a third link *c* will be raised up on the one side until the second link *b* is horizontal (Fig. 4), whereupon a channel of inverted U section is formed; as the motion progresses, the first link *a* will fall back into its original position in the grate, while a fourth link *d* will commence to be lifted.

If desired, when a wave has progressed from one end of the grate to the other, it may return, that is to say, supposing a wave has progressed from the rear to the front of the grate, it may return from the front to the rear of the grate, and this motion will be such that any holes on the firebed will be evened up. In this case, the roller 5 is caused to travel back and forth substantially at all times in raising relation to one or more links, i. e. on the guides 7. On the other hand, the waves may travel in one direction only or, alternatively, more frequently in one direction than the other, so that an automatic discharge of the ash, clinker, or the like rubbish is obtained. In the first case, the roller 5 is caused to travel in one direction in raising relation

to the links and in the other direction free of the links—which is accomplished by causing the cable 9 to move continuously in one direction. In the second case, the 5 roller is caused, for example, to move: (1) in raising relation to the links from front to rear of the furnace; (2) in raising relation to the links from rear to front of the furnace; (3) out of raising relation to the 10 links from front to rear of the furnace; (4) in raising relation to the links from rear to front of the furnace; and thereafter to repeat this cycle, in which waves twice move from rear to front, and once from front 15 to rear.

For these purposes, the cable 9 and therewith the carriage 6 and roller 5 are actuated from the electric motor 27 which by belt D drives the bevel gears 45 and the drum over 20 which the cable runs. The direction of rotation of the motor and hence the direction of movement of the cable 9 and roller 5 are determined by a reversing switch 12. This reversing switch 12 is actuated at 25 determined intervals by the mechanism shown on enlarged scale in Fig. 5. This consists of a frame having journalled there-in the two externally threaded spindles 20 and 21. The spindle 20 has keyed thereto 30 the driving pulley A, while a second driving pulley B is keyed to a gear 22 and revolves freely upon the spindle 20. A gear 23 on spindle 21 is of the same size as and meshes with gear 22 and is driven 35 thereby or drives it at its own speed as will be set forth. At the opposite end of the spindle 20 is keyed a further gear 25 which is in meshing engagement with a gear 24 keyed to spindle 21. Gear 24 has three 40 times as many teeth as gear 25, and spindle 21 has three times the linear pitch of the spindle 20. The belt C is driven from the belt transmission D as shown in Fig. 1, and may drive either of pulleys A or B.

Each of the spindles 20, 21 has a respective tappet 13, 14 thereon which are held 45 against rotation by the plate 26 and are internally threaded so as to be moved along the spindles during their rotation. This plate 26 also carries a pivot 28 for a rock 50 lever 29 whose arms project into actuating relation with the tappets 13, 14. In order to provide a rapid movement of the lever 29 when moved from position by one or the other of the tappets 13, 14, a spring 41 is 55 provided which is attached at one end to a point 42 of the frame and secured at the other to an arm 43 of the lever. The point 42, pivot 28, and arm 43 are approximately 60 in alignment at the greatest extension of the spring, so that the latter will snap the lever to its end position after a primary actuation by either of the tappets 13, 14.

The rock lever 29 is connected by an arm 65 30 with a lever 32 by a pin and slot connec-

tion 31; the lever 32 in turn moves the shifter rod 33 to right or left to move the belt (to the other of pulleys A or B).

Suppose for example it is desired to move the roller and in consequence the wave 70 caused by the roller twice in the direction rear to front of and above the grate for every movement from front to rear of and above the grate. It follows that in one cycle of the mechanism the time taken for 75 the roller 5 to move in the direction towards the front of the grate is three times that taken in the rearward direction since the carrier must travel: firstly, from rear to front above the rope drive; secondly, 80 from front to rear beneath the rope drive; and thirdly, from rear to front above the rope drive.

If therefore the roller is to cause a wave 85 to pass in one direction twice as often as in the other, the roller must move three times as far in one direction as the other; i. e. the motor should run three times as long in one direction as the other, or one 90 tappet must take three times as long to move the rock lever 29 as the other tappet takes.

Assume that the tappet 13 is at the left hand end of the spindle 20 and tappet 14 at the right hand end of spindle 21, and the belt C is on pulley A. Now as spindle 20 rotates, the tappet 13 moves toward the right; and as spindle 20 through gears 25, 24 drives spindle 21, the tappet 14 moves toward the left. This continues until tappet 100 13 strikes the rock lever 29 and causes it to be snapped to its opposite end position. The belt C is thus shifted to pulley B, and the motor 27 reversed. During the travel of tappet 13 toward the right, tappet 14 has moved 105 the same distance toward the left, as spindle 20 has been turning at three times the speed of spindle 21 which has three times the screw pitch. Gears 23 and 22 have been causing the pulley B to rotate loosely upon 110 spindle 20.

The belt C therefore now begins to drive the pulley B but in the direction opposite to that in which pulley A was rotated. By 115 gears 22, 23, spindle 21 is now rotated, and tappet 14 moves toward the right at a speed which is three times that at which it moved toward the left. At the same time, gears 24 and 25 cause the spindle 20 to rotate at three times its former speed and hence to return 120 tappet 13 toward the left at the same linear speed as tappet 14. Finally, the tappet 14 encounters rock lever 29 and moves it until the spring 41 causes the reversing switch 12 and the belt shifter 33 to be moved back into 125 their initial positions.

Hence, the electric motor 27 moves in one direction for three times as long as in the opposite direction, and therewith the cable 9. During the shorter time interval, the ca- 130

ble 9 draws the roller 5 from rear to front of the furnace, and the grate is moved. Reversal then occurs as set forth, and the cable 9 draws the roller 5 from front to rear and the grate is again moved during the first unit of the longer time interval; the cable 9 continues to pull in the same direction during the second time unit of this longer time interval and draws the roller idly back from rear to front without moving the grate; and as the cable 9 still continues to pull in the same direction, during the third unit of the longer time interval, the roller is drawn from front to rear and the grate is again moved. As the roller reaches the rear of the furnace, reversal again occurs, and the cycles of alternately longer and shorter time intervals continue.

Since the movement of the grate is dependent upon the relative gear ratio of the spindles, it is apparent that by a suitable change of this ratio, any desired movement may be given to the grate. If belt C is thrown off both pulleys A and B, the cable 9 runs in a single direction, and the grate is constantly moved from rear to front or vice versa.

The arrangement is applicable to any type of furnace where hand or automatic stoking is used either on the front or the rear of the furnace, or again where the fuel is partially coked in a closed tube in the upper part of the furnace and dropped on to the back of the grate.

I declare that what I claim is:

1. A furnace grate comprising a plurality of links connected together to form a flexible chain, means to raise said links successively to cause a hump therein to travel from end to end of the grate, and devices controlled in unison with the movement of said raising means to reverse the direction of movement of said hump.

2. A furnace grate comprising a plurality of links connected together to form a flexible chain, a freely rotatable roller arranged to form a hump or projection of some of said links above the others, a carrier to support said roller, means to move said carrier from end to end of the grate to cause said hump to travel from end to end of the grate, and devices controlled in unison with the movement of said moving means to reverse the direction of movement of said carrier.

3. A process of operating a flexible grate furnace which consists in depositing fuel upon said grate, passing a number of waves along the grate from one end to the other in one direction to lift and lower and advance the fuel thereon progressively, and

passing a greater number of waves in the opposite direction to lift and lower and advance the fuel on the grate progressively, so that the whole fuel bed gradually moves towards that direction in which the larger number of waves progress.

4. A furnace grate comprising a plurality of separate elements free to rise and fall, means to restrain said elements from longitudinal motion and means to cause a hump to travel progressively from one end of said grate to the other a larger number of times in one direction than in the other.

5. A furnace grate comprising a plurality of narrow bars, means to pivot said bars end to end to form a flexible sheet, means to fix the front and back edges of said sheet, means to cause a hump to travel from front to back edges of said sheet a plurality of times in one direction and thereafter to cause said hump to travel a plurality of times in the opposite direction.

6. A grate comprising a plurality of narrow bars, means interconnecting said bars end to end to form a flexible sheet of a predetermined length, means fixing the front and back edges of said sheet at a fixed distance apart less than the length of the sheet, means to take up the excess of length of the flexible sheet over the distance of separation length of its end supports, so that said excess is displaced from the horizontal plane to form a hump, and means to cause the hump to travel from one end of the grate to the other.

7. A flexible grate comprising a plurality of separate links, means to pivot said links end to end to form a flexible sheet, means to secure the front and back edges of said sheet at a fixed distance apart less than the length of the sheet, means to take up the slack in said sheet by successively raising the first-encountered end of a link, bringing the link to a horizontal position, and thereafter successively lowering the first-encountered end and the last-encountered end of the link and so lift and lower the links in sequence from one end of the grate to the other.

8. A flexible chain grate comprising links pivoted end to end, and means to move said links in turn firstly into a position inclined to the normal plane of the grate, secondly into a position in a plane parallel to the plane of the grate, thirdly into a position inclined to the normal plane but opposite to their first inclination, and fourthly back into the normal plane of the grate.

In witness whereof, I have hereunto signed my name this 5th day of March, 1920.

WILLIAM HERBERT NIELD.
